UNITED STATES PATENT OFFICE.

PAUL R. BROWN, OF COULEE, WASHINGTON.

ROTARY VALVE.

Application filed June 12, 1926. Serial No. 115,664.

The present invention relates to improvements in rotary valves for internal combustion engines, for distributing and controlling the admission of fuel charges to the cylinders of the engine and for exhausting the gases of combustion from the engine cylinders. A rotary valve is also used in connection with the engine for regulating or governing the admission of the charge to the cylinders, said valve being adjustable for varying the quantity of the charge passing from the distributing rotary valve to the cylinders. The distributing valve is operated with suitable timing gears or other mechanism from the engine, and is of the multiple type with inlet and exhaust ports angularly arranged for proper sequence in admitting fuel gas and exhausting spent gas to and from the engine cylinders.

Thermal-expansion devices are utilized in connection with the plurality of plugs of the multiple valve to move the plugs for the purpose of preventing sticking under high temperature in the walls of the valve casing, and other meritorious features are utilized in the combination and arrangement of parts as will hereinafter be more fully set forth and claimed.

In the accompanying drawings I have illustrated one complete example of the physical embodiment of my invention in connection with a four cylinder type of engine, wherein the parts are combined and arranged according to the best mode I have thus far devised for the practical application of the principles of my invention, but it will be understood that various changes and alterations may be made in the exemplified structure within the scope of my claim without departing from the principles of my invention.

Figure 1 is a transverse vertical sectional view at the head of an engine showing a cylinder, intake manifold and carburetor, the intake port for one cylinder and other features.

Figure 2 is a broken longitudinal sectional view of part of the engine illustrating an exhaust port and exhaust manifold.

Figure 3 is a longitudinal vertical sectional view as at line 3-3 of Figure 1 through the valve casing and showing the rotary valve in full.

Figure 4 is a detail sectional view of one of the valve plugs and part of another valve plug, illustrating in detail a thermostat con-

nexion between the adjoining valve plugs, which it will be understood are relatively movable longitudinally but rotate together.

In the drawings I have illustrated a conventional form of four cylinder internal combustion engine, but it will be understood that the rotary valve may be used in connection with six, eight and other types of engines. In order that the general arrangement and relation of parts may readily be understood I have indicated in Figure 1 one of the cylinders as 1 with its piston 2 and spark plug 3 in the cylinder head 4. At one side of the cylinder head is fashioned a longitudinally extending, horizontal valve casing 5 having an interior valve chamber 6, which as shown tapers from the left to the right end in Figure 3, and the usual water jacket 7 is provided for the valve casing in communication with the water jacket of the engine.

Each of the four cylinders of the engine is provided with an upwardly arched or curved intake port as 8, 9, 10, and 11 arranged transversely of the engine and extending from the cylinder to the intake manifold 12 which receives fuel gas from the carburetor 13.

The rotary distributing valve is of the multiple type and comprises a plurality of spaced, axially aligned, tapering plugs 14, 15, 16, and 17 located in the correspondingly tapered valve chamber. These plugs are relatively movable longitudinally of the casing, but are connected to rotate together and continuously when the engine is running, by means of short stud shafts 18 having keys 19 and extended at their ends into sockets 20 at the opposite ends of the intermediate plugs and provided in the inner ends of the end plugs. The valve stem 21 which is secured to the plug 14 is journaled in bearings in the screw plug 22 that closes one end of the valve casing, and a driven wheel 23 on the shaft and chain 24 are indicated as the valve operating mechanism actuated from the crank shaft of the engine for continuously rotating the multiple valve. The ports 25 for intake of fuel gas and the ports 26 in the plugs for exhaust of spent gases of combustion, are so arranged in combination with the valve operating mechanism and crank shaft of the engine as to admit fuel, and exhaust gases, in the proper sequences for running of the engine.

The inlet ports 25 which curve transverse-

ly through the plugs intermittently register with the inlet ports 8, &c., of the valve casing, and the exhaust ports 26 of the valve plugs intermittently register with complementary exhaust ports in the valve casing, indicated as 28 in Figure 2, it being understood that each cylinder has an exhaust port and the four exhaust ports dispose of the gases of combustion through the exhaust manifold 29 in Figure 2.

The multiple-plug valve is urged toward the smaller end of the tapering valve chamber by means of a spring 30 interposed between the end valve-plug 14 and the screw plug or closure 22 at the end of the valve chamber. However, to prevent sticking of the rotary valve within the walls of the valve chamber due to excessive heat from combustion within the cylinders or from the passage of the exhaust gases through the several valve plugs, thermal controlled means are provided for transmitting motion to the relatively, longitudinally movable plugs. Thus when the plugs are heated to such a temperature as might cause sticking of the plugs or a retardation of their rotary movement, under thermal expansion the plugs are slid or moved toward the larger end of the tapering valve chamber, thus compensating for the increased diameter of the plugs under heat expansion.

To cause this transmission of motion to the plugs, due to thermal expansion I employ a multiple-element thermostat comprising preferably alined, spaced bars 31 composed of material having a different coefficient of thermal expansion than the material of the plugs. These bars are interposed between adjoining valve plugs and between the smallest plug and the end wall of the valve chamber, with one end of the bar fixed in a plug and the outer, free end of the bar in contact with the face of an adjoining plug or against the inner face of the end wall of the valve chamber. By this arrangement of parts it will be apparent that under thermal expansion of the bars in

Figure 3 the spaced plugs will be moved to the left, the keyed short shafts 18 between the plugs permitting this sliding movement. 50

As best seen in Figure 4 the bar 31 extends into a large bore 32 arranged longitudinally of the plug and its threaded end 33 is screwed or passed through a reduced extension of the bore and secured by a nut 34 in the counterbore 35 at the opposite end of the plug. 55

The multiple rotary valve continuously rotates while the engine is running to distribute the fuel charges and to dispose of the gases of combustion. For regulating the admission of the fuel gas from the rotary valve to the cylinders I employ a regulating throttle valve 36 located between the distributing valve and the cylinders and arranged parallel with the rotary valve. A plurality of transversely curved ports 37 are arranged in the regulating valve to register with the several ports 8, 9, 10 and 11 of the valve casing, and the available openings for passage of fuel gas through these ports 37 are regulated by manually controlled operating mechanism 38 accessible as from the dash board or instrument board of an automobile. By manipulating the valve operating mechanism 38 the desired quantity of fuel gas may be admitted to the cylinders. 70 75

Having thus fully described my invention what I claim as new and desire to secure by Letters Patent is—

The combination with a tapered valve chamber and casing having inlet and exhaust ports, of a tapered rotary valve comprising spaced plugs having ports therein, keyed shafts connecting said plugs to permit longitudinal movement thereof, and thermal expansion bars carried by the plugs for contact with adjoining plugs for longitudinally moving said plugs. 80 85 90

In testimony whereof I affix my signature.

PAUL R. BROWN.
